UNITED STATES PATENT OFFICE.

ADRIAN A. FIRESTONE, OF CLEVELAND, OHIO.

SPRING-TIRE.

1,240,432.

Specification of Letters Patent. Patented Sept. 18, 1917.

Application filed October 18, 1916. Serial No. 126,257.

To all whom it may concern:

Be it known that I, ADRIAN A. FIRESTONE, a citizen of the United States, residing at Cleveland, in the county of Cuyahoga and 5 State of Ohio, have invented a certain new and useful Improvement in Spring-Tires, of which the following is a full, clear, and exact description.

This invention relates to certain improve- 10

ments in spring vehicle tires of the sort which include an endless wire coil. The object of the invention is to so construct such a tire and so mount it upon a wheel that the tire will be more durable and uniformly re- 15 silent.

The invention consists in the construction and combination of parts shown in the drawing, hereinafter described and definitely set forth in the appended claims.

20 In the drawing, Figure 1 is a sectional side elevation of a wheel equipped with this invention; Fig. 2 is a radial section of such a tire; Fig. 3 is a perspective view of one of the tire supporting blocks.

25 Referring to the parts by reference characters, 10 represents an endless spring coil or coil spring annulus. The ends of a spring coil may be connected together to form such an annulus by substantially the same means 30 which are shown and described for that purpose in my prior application Serial No. 45,119; except that the connectors 12 which are cast into the coil near its ends do not come to the ends, but are set back several 35 convolutions from said ends. Preferably one end of the coil has, as in the construction shown, four convolutions outside of the connector while the other end has five convolutions outside of the connector. This va- 40

riation is for the purpose of coming as near as may be to making the coil annulus equally resilient at all points. In the construction shown in said prior application there were about eight convolutions more or less, four 45 in each end of the spring rigidly embracing the connector, and these eight, more or less, adjacent convolutions had little or no resili- ent qualities. In the construction shown, however, in the drawing of this application

50 there are only three convolutions which are individually rendered non-resilient by each embraced connector, but these three convolutions are resiliently related to adjacent convolutions so that they may move circumfer- 55 entially as a unit toward and away from the same when the wheel is in service. Like-

wise between these two three-convolution groups, made non-resilient by the embraced connectors, are nine convolutions, the middle three of which are embraced by the arms of 60 a tread-plate as hereinafter described.

The wheel is represented by 14, and it is equipped with a metal felly band 15 which preferably should have a rather smooth outer periphery.

65 A series of coil-supporting blocks which are best made of wood 16 rest upon the external peripheral surface of said felly band, and are suitably spaced apart. It is with these blocks, and not with the wheel that 70 the inner periphery of the coiled annulus engages. In putting this coil spring annulus on the block encircled wheel, said annulus is stretched somewhat in diameter. Therefore, because of its tendency to return to its 75 normal condition it presses the blocks with considerable force against the periphery of the wheel; and this results in the partial embedding of the convolutions into the outer surface of said wood blocks. This is a good 80 practical way of producing what is cer- tainly desirable and is perhaps a necessary result, namely, that the blocks do not have any creeping movement with respect to the convolutions with which they severally en- 85 gage. This grip of the coil spring annulus should not, however, be so great as to prevent the circumferential creeping of the blocks upon the wheel under the conditions hereinafter set forth, and as tending to in- 90 sure this desired movement, said wood blocks are preferably soaked in oil.

95 To the ends of each of these blocks, thin metal plates 17 are secured, and they project outward and between convolutions 100 which rest upon the blocks and the adjacent convolutions. In the construction shown these blocks are of such length that three convolutions will rest upon each, and these plates 17 will go between the end convolu- 105 tions of this included group and the two convolutions adjacent the ends of said group.

20 represents tread plates. These are pref- erably made of metal, and each is provided with two inwardly projecting arms 21 adapt- 110 ed to go between two convolutions and these arms are so spaced apart that several (pref- erably three) convolutions will go between or be included by them. On the inner end of each of these arms is a finger 22 which goes in or under the adjacent non-included convolution. These tread plates are pref-

erably so proportioned and disposed that while each includes and embraces three convolutions, there will be between each pair of adjacent tread plates three excluded convolutions. Likewise the three convolutions which are included between the arms of a tread plate are the same three convolutions which rest upon an associated block 16.

These tread plates are fashioned to receive and hold tread blocks 25, which are preferably made of vulcanized rubber, although they may be made of any other suitable material. They may be held in recessed outer facings of the tread plates by means of transverse rivets 26.

There is secured to each side of the wheel felly a plate 30 which extends outward by the side of the wood blocks and the coil spring annulus, and the tread plates. These plates 30 act to exclude dirt and also to prevent any considerable lateral displacement of any of these parts with respect to one another or to the wheel; and these plates 30 should be constructed to withstand the strains to which they will thereby be subjected.

When a wheel is equipped with a tire constructed as above described, and is put into service, the action of the coil spring annulus will be substantially as follows, to wit: As each tread block comes in contact with the road surface it becomes subject to a stress which being transmitted through the included convolutions to the associated supporting block, tends to move that block circumferentially and does in most cases so move it.

The creeping movement of each wooden block which is associated with the tread block that is in contact with the road surface will not move far with respect to the adjacent blocks, because such relative movement is opposed by the adjacent convolutions. But this movement may be and will be sufficient to produce a satisfactory degree of resilience and to absorb to a sufficient degree such shocks as would otherwise be transmitted to the vehicle body or chassis frame.

Having described my invention, I claim:

1. The combination with a wheel having an encircling row of spaced blocks which are slidable on the outer periphery of said wheel, and a coil spring annulus which embraces the block-encircled wheel and bears against the outer surfaces of said blocks and holds said blocks tightly against the periphery of said wheel.

2. The combination with a wheel having an encircling row of spaced oil-soaked wood blocks which are slidable on the outer periphery of said wheel, and a coil spring annulus which embraces the block-encircled wheel and bears against the outer surfaces of said blocks and holds said blocks tightly against the periphery of said wheel.

3. The combination with a wheel having an encircling row of wood blocks which are slidable on the outer periphery of said wheel, and a coil spring annulus which embraces the block-encircled wheel and bears against the outer surfaces of said blocks and holds said blocks tightly against the periphery of said wheel, the convolutions of said annulus being partly embedded in the outer surfaces of said wood blocks.

4. The combination with a wheel having an encircling row of spaced blocks which are slidable on the outer periphery of said wheel, and a coil spring annulus which embraces the block-encircled wheel and bears against the outer surfaces of said blocks and holds said blocks tightly against the periphery of said wheel, each of said blocks being provided at its ends with outwardly projecting metal flanges which include a group of convolutions and project between the end convolutions of said group and the convolutions next adjacent thereto.

5. The combination of a wheel, a coil spring annulus mounted thereon, and a series of metal tread plates each having a recessed outer surface for the reception of a tread block and each having two inwardly projecting arms which include a group of convolutions and pass between the end convolutions of that group and the convolutions next adjacent thereto, which arms have circumferentially projecting fingers which lie inside of adjacent convolutions.

6. The combination of a wheel, a coil spring annulus mounted thereon, and a series of metal tread plates each having a recessed outer surface for the reception of a tread block and each having two inwardly projecting arms which include a group of convolutions and pass between the end convolutions of that group and the convolutions next adjacent thereto which arms have circumferentially projecting fingers which lie inside of adjacent convolutions, and there being a plurality of free convolutions intermediate of each group of convolutions included by arms of the tread plates.

7. The combination of a wheel having an encircling row of spaced blocks which are slidable upon the outer periphery of said wheel, a coiled spring annulus which embraces the block-encircled wheel and bears against the outer surfaces of said blocks and holds said blocks tightly against the periphery of said wheel, each of said blocks being provided at its ends with outwardly projecting metal flanges which include a group of convolutions and project between the end convolutions of said group and the convolutions next adjacent thereto, a series of metal tread plates, each having two inwardly projecting arms which include the same group of convolutions that are included between the metal flanges on one of

- said blocks, which arms pass between the end convolutions of the included group and the next convolutions adjacent thereto and have fingers which project inside of adjacent convolutions and there being a plurality of free convolutions intermediate of each group of convolutions included by arms of the tread plate and flanges of the blocks.
- 10 8. A spring tire for vehicle wheels which includes a coil spring annulus that contains connectors, each of which is tightly fitted within several of the convolutions of said coil spring annulus, and a bolt which connects said connectors together,—there being a plurality of convolutions between those convolutions within which said connectors are fitted.
9. A spring tire for vehicle wheels which includes a coil spring annulus that contains connectors, each of which is tightly fitted within several of the convolutions of said coil spring annulus, and a bolt which connects said connectors together,—there being a plurality of convolutions between those convolutions within which said connectors
- are fitted, and a plurality of tread plates each having two arms which include a group of convolutions and go between the end convolutions of the included group and the next adjacent convolutions, and each of said arms having a laterally extended finger which projects inside a convolution, two of said tread plates being severally so located that their arms include the groups of convolutions in which the two connectors are fitted, and one of said tread plates being located so that its arms include some but not all of the convolutions between the groups in which connectors are fitted, whereby there will be non-included convolutions between the last mentioned tread plate and those two tread plates which include the groups of convolutions which contain connectors.
- 15 10. A spring tire for vehicle wheels which includes a coil spring annulus that contains connectors, each of which is tightly fitted within several of the convolutions of said coil spring annulus, and a bolt which connects said connectors together,—there being a plurality of convolutions between those convolutions within which said connectors

In testimony whereof, I hereunto affix my signature in the presence of two witnesses.
